UNITED STATES PATENT OFFICE.

EDWARD R. ARMSTRONG, OF HOLLYOAK, DELAWARE, ASSIGNOR TO E. I. DU PONT DE NEMOURS & COMPANY, OF WILMINGTON, DELAWARE, A CORPORATION OF DELAWARE.

APPARATUS FOR CASTING COMPOSITION SHEETS.

Application filed October 14, 1924. Serial No. 743,590.

This invention relates to machines and methods for making sheets of material such as cellulose ester compositions, for example, celluloid and pyralin, by depositing a solution of the base material, for example, pyroxylin, upon a proper surface and then removing the solvents. Such a procedure I conveniently term "casting". In particular, the invention relates to machines for making such a sheet continuously and of any desired width and thickness, especially a relatively heavy sheet suitable for use in the arts in which cellulose ester plastics, made by making blocks and then sheeting the blocks, are applied, as for automobile windows, brush backs, and so on; and also relates to the making of striated sheets.

It has heretofore been the practice, in making stock for narrow, very thin strips, as photographic films, to cast the solution on wheels or drums, and this was feasible, for narrow, thin strips, as the relatively wide cast sheet could be cut longitudinally to provide several strips, giving a fairly high production in film feet. When, however, it becomes a question of making wide thick cast sheets, the casting-on-a-wheel method at once fails for practical purposes; not only is the wheel, for practical reasons, of necessity of limited width but, particularly, the solution deposit having to be large, per unit of wheel area, in order to give the desired thickness, which entails the removal of large amounts of solvent before the fresh film can be successfully stripped, the wheel movement must be excessively slow, giving an impossibly low production. The apparent alternative is to use a larger wheel, but this is plainly impractical; for example, a wheel to provide a circumferential distance from casting hopper to stripping point of about 350 feet—a distance frequently desirable to use to give high production—would be about 112 feet in diameter which is plainly a grossly impractical size.

Seeking to solve the problem thus presented, I turned to a casting machine of the belt type, that is, a machine whose casting surface should be a belt, it being evident that a belt machine, theoretically, could have a casting surface as long as desired. I found that a belt made up of a large number of plate sections jointed together to give

flexibility was impracticable due to the insuperable difficulty of providing hinging sections which could give the required smooth, unbroken, continuous casting surface. I have, however, solved the problem: I have devised a belt-type casting machine having an unjointed, flexible, continuous belt of long span and sufficient strength, with a smooth continuous casting surface. It is a major object of the invention to provide such a machine. It is also an object to provide a machine of the general character indicated by which striated sheets can be made; and it is a further object to provide a method, conveniently practiced with the aid of said machine, for making striated sheets. To these ends, and also to improve generally upon casting machines and methods, the invention consists in the various matters hereinafter described and claimed.

I am aware of abstract suggestions of continuous-belt casting made, evidently, by those who had not solved the problem of actually producing a casting machine embodying any such belt, this being evident from the fact that, as will appear hereinafter from the considerations set forth, the abstract suggestions of such a machine are by no means a solution of the problem since such solution primarily involves and presents the problem of actually providing a proper belt; this major consideration has been wholly passed over and ignored.

Without restricting the invention thereto, the same is described with more particular reference to the embodiment illustrated in the accompanying drawings, in which:

Figure 1 is a simplified sectional side elevation of the casting machine;

Figure 2 is a cross-sectional view substantially on the line 2—2 of Figure 1;

Figure 3 is a fragmental face view of the casting belt;

Figure 4 is a longitudinal section of the expansion device of the enclosure of the machine;

Figure 5 is an end view of the said expansion device;

Figure 6 is a side view of the shiftable take-up bearing of the machine;

Figure 7 is a fragmental section showing a structure for mounting the enclosure upon a bearing for a belt wheel.

Figure 8 is a vertical cross-sectional view of the casting hopper;

Figure 9 is a top plan view of the hopper;

5 Figure 10 is an enlarged fragmental vertical cross-sectional view of the lower portion of the hopper; and

10 Figure 11 is an enlarged fragmental bottom view of a group of the blades of the solution-dividing means of the hopper.

Referring now to the drawings and more particularly to Figure 1, the machine comprises a casting belt 1 carried by the belt pulleys or wheels 2, 3 and fully enclosed 15 substantially air tight by the casing 4 having the air outlet 5 and the air-intake fan 6. A solution trough 7 is carried by the casing 4 in position to discharge a sheet of solution across the width of the belt 1, such 20 trough being desirably of the type here illustrated (Figures 8 to 11) which provides for the making of striated sheets, for example factitious ivory, by the casting method. A stripping roll 8 extending across the 25 width of the sheet S of cast material, for example, pyroxylin, is mounted in position to receive the sheet and pass it to drying equipment (not shown). The belt is caused to travel by power applied to the driving 30 pulley 2^a on the shaft 2^b of the wheel 2. In operation, the (pyroxylin) solution P is continuously deposited on belt 1 and as the belt travels its circuit (clockwise in the drawing) the solvents are partially removed, leaving 35 the sheet S. The belt speed and solvent recovery rate are such that by the time any given portion of the sheet S has reached the roller 8, it is in condition to be stripped off in a self-sustaining continuous length. Such 40 solvent recovery apparatus, and so on, may be used as desired, the present invention not being primarily concerned with such features. It is to be particularly noted, however, that in order that the deposit may have 45 its solvent removed sufficiently slowly to give a proper and usable sheet it is advisable, with present day solvent recovery apparatus and so on, that the belt have a length of at least about 70 feet, with the spans about 30 50 feet; which indicates the necessity for a belt of considerable thickness to give the necessary strength.

In particular accordance with the present invention the belt is a single continuous 55 band of metal, highly polished and smooth. In my U. S. application entitled "Plating apparatus and product thereof", filed October 14, 1924, Serial No. 743,589, "Armstrong Case 1", I have disclosed a machine, and a 60 specimen procedure for operating the same, whereby such a band of indefinite length, any desired width, and—this is a most important point—of sufficient thickness and of such good quality as to give the necessary 65 strength, can be produced. Briefly, the belt

is made by electrolytic deposition or plating of a metal, preferably nickel, upon a cylindrical cathode, from which the deposited metal is stripped in a continuous band, the machine having provisions for continuous 70 operation, circulation of the bath, elimination of foam, constant brushing or clearing of the surface of the cathode and deposit, filtering of the circulating bath solution, and slow speed movement of the plating 75 surface. The nickel belt produced has a thickness of .01 inch to .05 inch, or greater if desired, and desirably .035 inch, a tensile strength between seventy and eighty thousand pounds per square inch, and, as produced for the present machine a width of about two feet four inches and a length of about eighty feet. To close the strip into a belt (see Figure 3) the abutting ends are dovetailed crosswise of the belt as at 1^a and 80 the joint silver brazed, an under strap 1^b and rivets 1^c being used if desired. While in the figure the joint line and rivets are shown, it is to be understood that, actually, the finishing and polishing are such that these points are practically invisible and the surface without inequality or flaw. The 85 belt, and joint, are highly polished in the usual ways of the nickel polishing art.

As to certain of the details of the illustrated machine:—The casing 4 is desirably of metal plates suitably held by suitable framing as will be understood by those skilled in the structural arts, such casing comprising the upper and lower reaches 9 and 10 and the drum-like ends 11 and 12 with which the reaches are tangentially connected. If desired, rollers 13 for supporting the belt may be provided in the casing. As indicated in Figure 2, wherein the lower 100 reach is shown of less cross section than the upper, the casing enlarges oppositely to the direction of travel of the belt providing for a decrease in the velocity of the air current as it reaches the successive points of increasing amounts of solvents to be removed.

The heads of the drums 11 and 12 may be connected about bearings, as 14 and 15 at each side of each drum, in any desired manner. As here shown, Figure 7, the bearing, as 15, supports, at 16, a collar 17 through which the shaft 18 of the wheel passes, and this collar has the wall or head 12^a of the drum fastened thereto. In this way the casing is held air tight upon the shaft.

It is highly desirable that, particularly along its upper span, where the solution is more fluid and therefore more liable to flow or shift to conform to any waves or non-levelness of the belt, the belt be held under sufficient tension to keep it flat; but as the belt is of metal it will contract and expand due to temperature changes. The present structure has provisions for maintaining the belt flat. As here shown, there are pro- 125

vided equalizing structures 19, 19, one in each reach of the casing and the like bearings, as 15, one at each end of shaft 18 of the wheel 3 are urged in a direction to carry 5 the wheel 3 away from the wheel 2, the expansion devices providing for these changes in the length of the casing 4 which are caused by the shifting of the drum 12 when the bearings shift.

10 Each bearing 15, as here shown (Figure 6), comprises a bearing proper 20 which supports the shaft 18, this bearing being mounted upon the slideway block 21 (suitably stationarily mounted upon supports 15 rising from the floor) for movement to and fro thereon in the longitudinal direction of the belt 1, the bearing and block having co-operative slideways and tracks 20^a and 21^a as indicated. For urging the bearing 20 in 20 the direction to take up slackness in the belt, there is provided the expanding spring 22 having one end received in the socket 23 of the bearing member 20 and the other abutting the abutment block 24. The block 25 24 is adjustable to change the force of the spring, it being shown as forming the end of a screw 25 threaded through the projection 26 from the stationary slideway block. The screw carries a handle 27 for 30 turning the same, and a lock nut 28. With this construction on the bearings 15 which carry the wheel 3 are urged away from the wheel 2, with a force that can be regulated as desired by adjustment of the screw 25. It will 35 be understood that the springs are adjusted to such tension as to permit retreat of the bearings 15 upon contraction of the belt.

The illustrated expansion devices, heretofore designated generally as 19, for permitting changes in the length of the casing as 40 the wheel 3 shifts, carrying the drum casting 12 with it, are as follows, see Figures 4 and 5. Each expansion device is made up of four corrugated sheets, as 19^a, of 45 metal, one for each side. These are mitered and brazed or soldered together at the corners as indicated at 29, making a box-like structure open at the ends. At each end the structure 19 is carried by a rectangular 50 frame, as 30, abutting a mating-frame 31, the metal sheets of the casing proper 4 and of the structure 19 being out-turned and held between the frames as shown. While 55 various materials and detailed dimensions for the structure 19 may be used, I have found that, in a structure having its inside crosswise dimensions 2 feet 4 inches by 5 $\frac{1}{8}$ inches, and about 1 foot long, copper sheets .0375 inch thick and having 5 corrugations 60 at about 30° angles and about 2 inches deep are satisfactory as readily providing for such movement as is called for in taking care of about an eighty-foot belt of nickel.

The solution trough, heretofore designated 65 generally as 7 is, in preferable accordance

with the invention and as here shown, more particularly in Figures 8 to 11, of a character to provide for the casting of a striated sheet, as factitious ivory. Such striated sheets have heretofore been made by the tedious process of making sheets of the individual colors, pressing the sheets (laid alternately) into a block, and sheeting the block across the grain. With the present device the sheets can be originally made in 75 striated form. The trough 7 comprises the general hopper body 32 made up of the end walls 32^a, 32^b, and side walls 32^c, 32^d suitably fastened to the end walls, the side walls, at the terminations of their inclines 32^c, 32^d 80 being spaced to provide the discharge slot 33 extending longitudinally across the bottom of the hopper body. The hopper body is divided lengthwise by the wall 34 forming separate solution chambers 35^a, 35^b. At the 85 base of the wall is provided structure, designated generally as 36, whereby the solutions P^w and P^c, flowing from the hopper chambers, are caused to meet and join in streams. These streams as they are cast on the casting 90 surface, (belt 1) give a sheet S with the deposits from the solutions joined in striæ running longitudinally of the sheet. For instance, if solution P^w be taken as white and solution P^c as cream, there will be produced 95 striated goods having the appearance of ivory.

The structure 36 comprises a series, longitudinally of the hopper, of flow separators 100 36^a. Conveniently the wall 34 and structure 36 are integral and desirably as illustrated. Here, the wall 34 is made up of a series of blades or units each presenting a pointed portion 36^a, and held in position centrally of the hopper and solution tight by through 105 bolts 37. The pointed portions of immediately adjacent blades are out of register with each other, as indicated more particularly in Figure 10, the alternate points being in alignment. This may be conveniently accomplished by making the blades all alike, and with their points out of alignment with the central axis of the blade, and assembling the blades with immediately adjacent blades facing in opposite directions, that is, with 110 alternate blades facing in the same direction. This provides a structure which maintains the separation of the solutions until the outlet 33 is substantially reached and yet discharges the solutions in longitudinally contacting streams, each stream from a given chamber of the hopper running down between the side of the hopper and the edge 115 33^a of the blade which separates into streams the flow from the other chamber. While 120 various specific dimensions for the points of the blades may be used, I have found that a distance between the points, crosswise the hopper discharge slot, of .03 inch, whereof 125 each individual solution outlet, with blades 130

about .03 inch thick, will be about .03 x .03, satisfactory. With a hopper about 1 foot long about 375 blades or sheets are thus required. Evidently, upon the widths of the 5 blades will depend the widths of the striæ, so these may be made as desired by using particular blades, of the same or different widths, or by facing several immediately succeeding blades in the same direction, and 10 so on. Control of the amount of solution discharged from a chamber per unit of time and of relative amounts discharged, may be provided for in any desired manner. As here shown, control is provided by controlling 15 the head of the solution. Thus, in Figure 8 separate solution inflow pipes 38^e and 38^w, and overflow pipes 39^e and 39^w are provided, the overflow pipes of course determining the heads of the solutions. By way 20 of example merely, the pipe 39^w is placed higher than the pipe 39^e, giving a greater head, and consequently a greater flow, to the solution in the compartment 35^w. The solutions used may be of the kinds usual in the 25 art and containing the base material, for example pyroxylin, suitable solvents, and pigment. For example, there may be used in making factitious ivory:—a white solution, comprising nitro-cotton 26, camphor 8, zinc 30 oxide 3, ethyl alcohol 6, acetone 57 (parts by weight), and a cream solution like the white except that somewhat less zinc oxide is used, say 2.5 parts, whereby the yellowish natural 35 color of the unpigmented solution is not fully obscured. It will of course be understood that any combination of colors desired may be used, and the desirable viscosity of the solutions under any particular circumstances will be quickly arrived at by those 40 skilled in the art. Although particular reference has been made to a double-flow hopper it will be understood that a single-flow hopper can be used if it be desired to produce merely a plain sheet. The removal of the 45 solvents, solution deposits per unit of area, and like well understood factors, present no new problems and with them the present invention is not primarily concerned, the usual practices of the art being satisfactory.

50 I claim:

1. A machine for casting solutions into sheets comprising a belt-line casting surface member, such member being a continuous sheet entirely of electrolytically deposited 55 nickel having a thickness of at least substantially .01 inch.

2. A machine for casting solutions into sheets comprising a belt-like casting surface member, such member being a continuous 60 sheet entirely of electrolytically deposited nickel and having a thickness substantially between .01 and .05 inch and a tensile strength substantially between 70 and 80 thousand pounds per square inch.

65 3. A machine for casting solutions into

sheets comprising a belt-line casting surface member, such member being a continuous sheet entirely of electrolytically deposited nickel having a thickness of substantially .01 to .05 inch.

70

4. In a machine of the character indicated, in combination, a closed belt, means supporting the belt, such means being shiftable to maintain the belt taut, an essentially rigid structure enclosing the belt, such structure having a portion connected with said supporting means to shift therewith, and provisions associated with said structure providing for the shifting of said portion with said supporting means without disruption of said structure.

75

5. In a machine of the character indicated, in combination, a closed belt, means supporting the belt, such means being shiftable to maintain the belt taut, an essentially rigid structure enclosing the belt, such structure having a portion connected with said supporting means to shift therewith, and provisions associated with said structure providing for the shifting of said portion with said supporting means without disruption of said structure, said structure comprising upper and lower tunnel-like reaches enclosing the belt, and said provisions comprising expansion-and-contraction sections 90 inserted in said reaches.

85

6. In a machine for casting a solution into a sheet, in combination, a closed metal belt presenting the casting surface, a pair of belt wheels for supporting the belt and encompassed within the spans of the belt, an essentially rigid enclosing structure for the belt and wheels, shiftable bearings for one of said wheels, a portion of said structure being connected with said bearings to shift therewith, and means associated with said structure providing for the shifting of said portion with said bearing without disruption of said structure.

100

7. In a machine for casting solutions into a striated sheet, in combination, a casting surface device having a casting surface of a width to receive a plurality of simultaneously deposited solution streams thereon, side by side, and a device for depositing said streams in merging relation, one of said devices being movable relatively to the other whereby said deposits shall extend along said casting surface, said depositing device comprising a receptacle divided into solution chambers, and means adjacent the bottom of the receptacle for dividing the several flows into streams and interspersing the streams from the several flows, such dividing means comprising a bank of non-registering blades with certain blades extending to one side of the hopper and spaced from the other side and other blades reversely arranged.

115

In testimony whereof I affix my signature.
EDWARD R. ARMSTRONG.

CERTIFICATE OF CORRECTION.

Patent No. 1,672,403.

Granted June 5, 1928, to

EDWARD R. ARMSTRONG.

It is hereby certified that error appears in the printed specification of the above numbered patent requiring correction as follows: Page 4, line 35, for the misspelled word "coure" read "course"; same page, lines 52 and 66, claims 1 and 3, for the compound word "belt-line" read "belt-like"; and that the said Letters Patent should be read with these corrections therein that the same may conform to the record of the case in the Patent Office.

Signed and sealed this 3rd day of July, A. D. 1928.

(Seal)

**M. J. Moore,
Acting Commissioner of Patents.**
